UNITED STATES PATENT OFFICE.

RICHARD F. DOWNEY, OF MILWAUKEE, WISCONSIN, ASSIGNOR OF ONE-HALF TO HUGO LOEWENBACH, OF MILWAUKEE, WISCONSIN.

WASHING-MACHINE.

1,102,395.

Specification of Letters Patent.

Patented July 7, 1914.

Application filed September 17, 1913. Serial No. 790,160.

To all whom it may concern:

Be it known that I, RICHARD F. DOWNEY, a citizen of the United States, and resident of Milwaukee, in the county of Milwaukee and State of Wisconsin, have invented certain new and useful Improvements in Washing-Machines; and I do hereby declare that the following is a full, clear, and exact description thereof.

10 The object of my invention is to provide a simple, economical, effective and durable washing machine, the same being especially adapted for household use whereby dishes or other articles can be quickly and sanitarily cleansed with slight exertion on the part of the operator.

With the above objects in view the invention consists in certain peculiarities of construction and combination of parts as hereinafter set forth with reference to the accompanying drawings and subsequently claimed.

In the drawings Figure 1 represents a longitudinal sectional view of a washing machine embodying the features of my invention, the section being indicated by lines 1—1 of Figs. 2 and 3; Fig. 2, a cross-section of the same, the section being indicated by line 2—2 of Fig. 1; Fig. 3, a detailed fragmentary view of one of the drum heads showing certain gear connections; Fig. 4, a detailed cross-sectional view of a porous dish-receiving tray, the same being shown removed from the drum; Fig. 5, a detailed cross-sectional view of an auxiliary basket adapted to fit within the tray for holding certain small articles to be washed; Fig. 6, a fragmentary top plan view showing one end of a water scoop, a pair of which are utilized in connection with the drum for distributing water in a washing operation, and Fig. 7, a detailed cross-section of a tray-supporting bracket illustrating a portion of the bracket fitted therein, the section being indicated by line 7—7 of Fig. 1.

Referring by characters to the drawings, 1 represents a portable circular drum adapted to contain water at a predetermined level, having skeleton supporting feet 2. The top portion of the drum wall is cut away to form an opening 1' for access thereto, whereby dishes or other articles to be washed may

be inserted. The opening 1' is closed by a circular lid 2', which lid is in hinge connection with one edge of the drum body and the free edge of said lid is secured to the opposite edge of the drum body by a hasp 3, as best shown in Fig. 1. The drum is formed with solid heads 1'', which heads together with the cylindrical walls are bound by a horizontally disposed reinforcing band 4, one horizontal stretch of which is alined with one edge of the drum opening. The band stretches which abut the drum-heads, together with said drum-heads, are apertured approximately centrally of the same to form journals for drive studs 5, as best shown in Fig. 1. Each of the drive studs project beyond the adjacent band stretch and has secured thereto a toothed pinion 6 and also the downturned end of a bail 7, through which bail said studs are connected and oscillated incidental to the application of power by the operator. The inner ends of the drive studs 5 project through the drum heads and are each squared for the reception of a hanger 8, the pair being rigidly connected to a segmental hollow scoop A. Each band and drum-head 1'' is also apertured for the reception of a second set of driven studs 5', each of which studs carries externally of the drum-head a pinion 6' that meshes with the corresponding pinion 6 of the juxtaposed drive stud. Hence when motion is imparted to the drive pinion 6 through the bail 7, it is transferred to the driven pinion 6'. The inner ends of the driven studs 5' are likewise squared for the reception of hangers 8', which hangers constitute parts of a segmental scoop B, the latter being a duplicate of the previously described scoop A and, as shown in Fig. 2, each of the scoops, when at rest, is positioned adjacent to the bottom of the drum in close proximity to each other, being arranged upon either side of an imaginary vertical line intersecting the center of the drum-head. The scoops extend throughout the length of the drum and have closed inner end and bottom walls 10, 10', respectively. A top wall 11 parallels the bottom wall 10' and, together with the latter, terminates to form a discharge mouth opposite the inner closed end wall, which mouth is adapted to

deliver a vertical stream of water when the tray is oscillated from its position of rest to the extreme of its movement or approximating this position. The top wall 11 is interrupted adjacent to the inner end wall 10 to form a water discharge mouth 12 that extends the length of the scoop. The mouth 12 is arranged to deliver a side or approximately a horizontally disposed stream of water in the operation of the scoop, said mouth being partially covered by a perforated plate 12', whereby the flow of water is retarded and a portion thereof is caused to fall or be thrown out in spray-like form. 10 To further direct the side delivery stream of water the inner edge of the discharge mouth 12 terminates with an outwardly flanged lip 12''. Each scoop is also divided into a side delivery and a vertical delivery compartment *a*, *b*, respectively, by an obliquely disposed partition plate 13, which plate extends from the bottom wall 10', adjacent to its junction with the end wall 10, to the top wall 11 adjacent to the vertically disposed discharge mouth. 15

Projecting upwardly from the central portion of the drum bottom and between the scoops A and B are a pair of spaced tray-supporting ears 14, which ears perform 20 their function in conjunction with a pair of aligned guide brackets 15, each being secured to one of the drum heads by means of offset pads 15'. The brackets 15 are also provided with inwardly extended flanges 15'' having 25 flared upper terminals whereby a removable dish-receiving tray C is seated, the same being hereinafter more fully described.

As best shown in Figs. 1 and 4, the dish-receiving tray C is semi-circular in cross-section and its bottom and side walls are formed from a single sheet of wire screen-cloth 16, or other suitable porous material, which screen-cloth is secured to a frame comprising end plates 17 and horizontally arranged binder-strips 18 for the edges of said screen-cloth, the said strips being connected to the end plates. The tray is further reinforced by a centrally disposed backbone strip 19 having upturned shoe portions 19' that are fastened to the end plates and are arranged to engage the tray-supporting brackets 15 between their flanged edges, whereby said tray is seated within the drum with its bottom disposed approximately 30 parallel to the drum bottom in such manner to permit both water scoops to nest therewith when the latter are at rest. The porous tray is also provided with wire looped end handles 20, which handles are secured to the 35 end plates 17 for convenience in manipulation and, as shown, the bottom of the tray is also provided with a series of rack loops 21 at one end for the reception of vessels or other articles to be cleansed, such articles

being thus held apart, whereby the various 65 surfaces are exposed to the several flows of water directed thereon by manipulation of the water scoops.

As shown in Figs. 5 and 1, the dish-receiving tray C may also contain an auxiliary 70 detachable basket D, which basket is adapted to hold small articles such as knives, forks, spoons, or the like. This basket D is preferably semi-circular in shape to nest firmly within the tray and at one end thereof, being much shorter in length as compared to the length of the tray. The body and side walls of the basket, as shown, are formed from wire screen-cloth or other perforated material supported upon a suitable skeleton 75 frame, the bottom and side bars of which frame are connected by rack pins 23, whereby articles grouped may be held in spaced relation to more effectually expose them to the influence of the variously directed 80 streams of water.

One of the drum-heads 1'' is provided with a drain nozzle 24, which nozzle, as shown, is closed by a cork for convenience of removal, whereby foul water is drawn from 90 the drum, it being apparent that, in operation, the drum is filled with hot or boiling water to a desired level as indicated at *x* Fig. 2. In practice to accomplish the greatest efficiency any scouring compound or 95 soap is mixed with the cleansing water, whereby grease or other particles are caused to be more effectually removed from the surfaces of the dishes or other vessels being washed. 100

In the operation, the drum is filled with the washing fluid to a point approximately indicated by the dotted lines marked *x*. Thereafter the soiled dishes are placed in the tray, certain types of which are adjusted 10 between the rack loops, while cups or like articles are placed at that end of the tray clear of the rack. Knives, forks and spoons or similar articles are assembled in groups within the removable basket D and 11 thereafter the said basket is placed in the position shown within the tray and at one end thereof. The lid 2' of the drum being open the loaded tray is then dropped into position within the drum, as best shown in 12 Fig. 1. In this position the shoe portions 19' of the tray backbone are fitted between the flanges 15'' of the brackets 15 and the backbone of said tray rests upon the supporting ears 14, whereby the tray is held 13 suspended from the bottom of the drum and parallel thereto, the space between the tray and bottom being occupied by the water scoops A and B. The water scoops, being submerged and filled with the washing fluid, 14 are now in their position of rest, as shown in Fig. 2. The lid 2' is then locked down and the bail 7 is oscillated in the direction

indicated by the arrow in Fig. 2. This movement causes the water scoops to rise in opposite directions as indicated by the arrows, and as the oscillatory movement is quickly effected a certain amount of water contained in the compartments *a* will be immediately thrown out toward the center of the drum in approximately horizontal streams, which streams meet or contact with the articles to be washed. A further movement of the scoops in the same direction will cause the remaining quantity of water in the pockets *a* to be thrown out or drained in spray form due to the fact that the water is forced through the perforated plates 12' which partly close the side delivery mouths 12. Coincident to the rise of the scoops just described after the same have reached a certain point in their elevation the washing fluid or water contained in the pockets *b* will be thrown outwardly from the mouths of said pockets and meeting at the center of the drum will fall in a vertical stream upon the articles to be washed, said pockets being drained due to the momentum imparted to the scoops as they travel together above the tray. The bail 7 is then reversed and the scoops returned to their position of rest where they receive fresh charges of the washing fluid and are again elevated by the oscillatory movement imparted to said bail. Thus a succession of side delivery streams are thrown upon the articles being washed and also vertical streams of the washing fluid, said streams commingling in the action and causing cross current which will thoroughly envelop the soiled dishes to cleanse them of all foreign matter. After the washing operation has been completed the tray, together with the auxiliary basket, is removed from the drum and placed or suspended in any suitable position, whereby the now cleansed articles are exposed to the air for drying.

Particular attention is called to the fact that, owing to the oscillatory action of the scoops, volumes or streams of water are thrown in all directions upon the articles being washed, said scoops being so arranged and connected that they will oscillate from a point under the tray to a point above the tray and discharge water throughout their upward or working oscillatory movement.

While I have shown one form of my invention and described the details of construction minutely, it is understood that I do not limit my invention to such details, but reserve the right to vary the same within the knowledge of skilled mechanics for accomplishing the desired result. It is also obvious that, owing to the fact that the bail connects both drive studs, the power will be applied equally to the ends of the scoops, the bail being also utilized as a means for

carrying the washing machine from place to place.

I claim:

1. A washing machine comprising a drum, a porous tray detachably seated therein above the drum bottom, and a pair of oscillatory water scoops in geared connection arranged to oscillate in opposite directions from a filling point beneath the tray to a discharge point above said tray.

2. A washing machine comprising a drum, a porous tray detachably seated therein and spaced above the bottom, a pair of oscillatory water scoops suspended from the drum arranged to normally rest below the tray and to be lifted to a discharging position above said tray, separate water compartments in each scoop, and a geared connection between the scoops whereby they are actuated.

3. A washing machine comprising a water receiving drum having heads, pairs of gear connected studs mounted in each head, scoops suspended from the studs, separate open mouth compartments in each scoop whereby independent streams of water are taken up and discharged, tray-supporting means in connection with the drum heads, a porous tray arranged to be seated upon the tray supports above the scoops when the latter are at rest, and actuating means in connection with one pair of the studs.

4. A washing machine comprising a water receiving drum having heads, pairs of gear connected studs mounted in each head, scoops suspended from the studs, separate open mouth compartments in each scoop whereby independent streams of water are taken up and discharged, tray-supporting means in connection with the drum heads, a porous tray arranged to be seated upon the tray supports above the scoops when the latter are at rest, and an actuating bail secured to one pair of the studs whereby the scoops are simultaneously lifted from their position of rest under the tray to positions over said tray.

5. A washing machine comprising a water receiving drum having heads, pairs of gear connected studs mounted in each head, arms secured to the studs, scoops suspended from the arms, separate open mouth compartments in each scoop, perforated plates arranged to partially close one set of the scoop mouths, flanged brackets secured to the drum heads, a porous tray having shoes adapted to engage the flanged brackets, and an actuating bail having ends rigidly secured to one pair of the studs.

6. A washing machine comprising a drum, a porous tray detachably seated therein, the same being suspended above the bottom of said drum, a pair of oscillatory segmental scoops suspended from the drum

and adapted to normally rest under the tray, |
gears connecting the scoop suspension |
means, and a partition plate in each scoop |
whereby the same is divided into separate |
5 water compartments, each compartment |
having a discharge mouth.
In testimony that I claim the foregoing

I have hereunto set my hand at Milwaukee |
in the county of Milwaukee and State of |
Wisconsin in the presence of two witnesses. 10 |
